UNITED STATES PATENT OFFICE

151,372

DESIGN FOR A CLOTHES HANGER

Leona S. Keefer, Dayton, Ohio

Application April 3, 1946, Serial No. 128,209

Term of patent 14 years

(Cl. D80—8)

To all whom it may concern:

Be it known that I, Leona S. Keefer, a citizen of the United States, residing at Dayton, in the county of Montgomery and State of Ohio, have invented a new, original, and ornamental Design for Clothes Hanger, of which the following is a specification, reference being had to the accompanying drawings, forming a part thereof:

In the drawings,

I claim:

The ornamental design for a clothes hanger, as shown.

LEONA S. KEEFER.
